ROBERT M. PHINNEY, OF ROCHESTER, NEW YORK, ASSIGNOR TO GENERAL RAILWAY SIGNAL COMPANY, OF ROCHESTER, NEW YORK

TRAIN DISPATCHING SYSTEM FOR RAILROADS

Application filed July 26, 1929. Serial No. 381,288.

This invention relates to train dispatching systems of the synchronous selector type, and more particularly to means for transmitting indications from distant way stations to the dispatcher's office.

In order to transmit a plurality of distinctive indications from a distant way station to a local dispatcher's office over the same channel of a synchronous selector dispatching system, it is found expedient to apply a direct current polarity to a message channel at a distant way station, so that at least two indications can be given depending on the polarity of such direct current source. From this it readily appears that a separate source of current is required at each way station for transmitting such indications from the way stations to the dispatcher's office. In order to economize in these direct current sources of potential, or batteries, it is proposed in accordance with the present invention to combine the voltage applied at such distant way station with a voltage located in the dispatcher's office, as a result of which the voltage of the direct current source at the way stations need only be half as high as would otherwise be required to get the same current flow.

Other objects, purposes and characteristic features of the invention will in part appear from the accompanying drawings and will in part be pointed out in the specification hereinafter.

In describing the invention in detail reference will be made to the accompanying drawings, in which the apparatus in the dotted rectangle represents the apparatus in the dispatcher's office, and the remaining apparatus represents that located at a distant way station.

The invention, as shown, in the drawings has been shown applied to a synchronous selector system of the rotating arm type, such as shown in the application filed by R. C. Leake, Ser. No. 321,186, filed November 22, 1928, to which reference may be had for further information as to how the rotating arms A and A¹ are rotated in synchronism. For the purpose of the present application we will assume that the rotatable arms A and A¹

are continually rotated in synchronism, by suitable means not forming a part of the present invention. These arms simultaneously engage corresponding stationary contacts, of which the contacts for the arm A have been designated 13, 14, 15, and 16, and the stationary contacts for the arm A¹ have been designated 13¹, 14¹, 15¹ and 16¹. 55

The portion of the railway system shown includes track rails 1, divided by insulating joints 2 into track sections, of which the track section shown is provided with the usual closed track circuit including a track battery 3 and a track relay T. In the dispatcher's office, conventionally shown by the dotted rectangle DO, is located indicating lamp I, which if illuminated manifests occupancy of the track circuit including the track relay T. This indicating lamp I is controlled by the indicating relay IR, which relay is one of the direct current polar locking type. This relay IR is operated to a position depending on the polarity of the current flowing therethrough, and remains in such position until energized by direct current of reverse polarity. The dispatcher's office also includes neutral relays R¹ and R², the function of which is more readily described in the operation of the system. 75

Operation.—In order to get a more clear understanding of the operating characteristics of the system, let us observe the message circuit which is momentarily closed when the contacts A and A¹ engage the stationary contacts 15 and 15¹. At this time the following message circuit is momentarily closed:—beginning at the positive terminal of the battery 20, wire 21, front contact 22 of the track relay T, wire 23, contacts 15¹—A¹, wire 24, message wire 25, contacts A—15, wire 26, winding of indicating relay IR, wire 27, contacts 28 of the relay R¹, assuming its retracted position, wire 29, front contact 30 of the relay R², wire 31, one-half of the battery 32, 95 common return wire C, and wire 33 back to the midpoint of battery 20.

It will be noted that the batteries 20 and 32 are connected in series in such a way that their voltages oppose each other, so that no 100

current flows in the circuit just traced and the indicating relay IR is not operated.

Let us now assume that a train moving along the track treads upon the track circuit containing the track relay T, and thereby shunts this track relay T, and causes it to assume its retracted position. Under this condition of the track relay T the following circuit for the indicating relay IR is closed:—beginning at the middle connection of the battery 20, wire 33, common return wire C, the positive half of the battery 32, wire 31, contact 30 of the relay R², wire 29, back contact 28 of the relay R¹, wire 27, winding of the indicating relay IR, wire 26, contacts 15—A, wires 25 and 24, contacts A¹—15¹, wire 23, contact 22 of the track relay T in its retracted position, and wire 34 connected to the negative terminal of the lower half of battery 20. It will be noted that the midpoint of battery 20 and the midpoint of the battery 32 are connected to the same wire, so that their voltages are accumulative if the remaining part of the circuit leads from the negative terminal of battery 20 and the positive terminal of battery 32, thereby causing current to flow through the indicating relay IR in a direction to operate it into its left-hand position.

Operation of the relay IR to its left-hand position illuminates the indicating lamp I through the medium of closure of contact 35 of this relay IR. Also, this operation of the relay IR to its left-hand position causes the contact 36 to break the energizing circuit for the relay R², thus de-energizing this relay IR², and completes an energizing circuit for the relay R¹, so that the circuit through the indicating relay IR just traced is shifted to include the negative half of the battery 32, instead of the positive half of this battery. From this it readily appears that during subsequent closure (after de-energization of relays R² and energization of relay R¹) of the modified message circuit, will cause no current flow in the message circuit because the batteries 20 and 32 will again oppose each other. This modified message circuit including opposing voltages may be traced as follows:—beginning at the negative terminal of the battery 32, wire 37, front contact 28 of the relay R¹, wire 27, winding of the relay IR, wire 26, contacts 15—A, wires 25 and 24, contacts A¹—15¹, wire 23, contact 22 of the track relay T in its retracted position, wire 34, negative half of the battery 20, wire 33, common return wire C connected to the midpoint of battery 32. It readily appears that the upper half of the battery 32 now opposes the lower half of the battery 20, so that no current will flow in the relay IR and it will remain in its left-hand position.

Applicant has thus provided a system wherein the sources of current for transmitting an indication function over a message

circuit are connected in series and are located respectively in the dispatcher's office and at a distant way station, so that each way station will require a battery of half the voltage that is required to transmit the same amount of current over the same circuit and indicating relay, the battery in the dispatcher's office being usable in connection with batteries at each of a large number of way stations, only one way station having been shown for convenience, so that quite a saving in batteries or other sources of direct current is made. The track relay T² has its front contact 40 similarly connected into a message circuit including the wire 41 at the dispatcher's office, said wire 41 being connected to similar apparatus as is the wire 26 corresponding thereto, which apparatus has for convenience been omitted.

Attention is directed to the fact that each time the indicating relay IR is operated it reverses the polarity of the direct current source included in series in the message circuit at the dispatcher's office. This has a further advantage in preventing current flow in the message circuit at all times except when the indicating relay is to be operated to the reverse position from which it assumes. This is not only economical as far as the electrical energy is concerned but prevents additional sparking at the contact arms A and A¹ and prevents the wear that usually accompanies such sparking.

Having thus shown and described one rather specific embodiment of the present invention, it is desired to be understood that this has been done for the purpose of showing one application of the invention to facilitate describing the same, and it is to be understood that various changes, modifications, and additions may be made to adapt the invention to other uses and other synchronous selector systems such as systems of the stepping relay type, all without departing from the spirit or scope of the present invention or the idea of means underlying the same, except as demanded by the scope of the following claims.

What I claim as new is:—

1. In a train dispatching system of the synchronous selector type, the combination with a plurality of message circuits closed sequentially and connecting a dispatcher's office and a plurality of way stations, of a source of current in said dispatcher's office common to all of said message circuits, and another source of current in each of said message circuits at the way station end of such message circuit, whereby message current will flow if the voltages of the sources of current in a particular message circuit are cumulative.

2. In a train dispatching system of the synchronous selector type, the combination with a plurality of message circuits closed sequentially and connecting a dispatcher's

5 office and a plurality of way stations, of a source of current in said dispatcher's office common to all of said message circuits, another source of current in each of said message circuits at the way station end of such message circuit, and traffic controlled means for closing said message circuit at a point distant to said dispatcher's office.

10 3. In a train dispatching system of the synchronous selector type, the combination with a plurality of message circuits closed sequentially and connecting a dispatcher's office and a plurality of way stations, of a source of current in said dispatcher's office common to all of said message circuits, another source of current in each of said message circuits at the way station end of such message circuit, and traffic controlled means at such way station for at times closing said message circuit.

15 4. In a train dispatching system of the synchronous selector type, the combination with a plurality of message circuits closed sequentially and connecting a dispatcher's office and a plurality of way stations, of a source of current in said dispatcher's office common to all of said message circuits, another source of current in each of said message circuits at the way station end of such message circuit, and traffic controlled means for at times including said another source of current in such message circuit so as to be poled in one direction and at other times so as to be poled in the other direction.

20 5. In a train dispatching system of the synchronous selector type, the combination with a plurality of message circuits closed sequentially and connecting a dispatcher's office and a plurality of way stations, of a source of current in said dispatcher's office common to all of said message circuits, another source of current in each of said message circuits at the way station end of such message circuit, traffic controlled means at such way station for at times closing said message circuit, and means at the dispatcher's office for at times reversing the polarity of the source located at said dispatcher's office in a particular message circuit.

25 6. In a train dispatching system of the synchronous selector type, the combination with a plurality of message circuits closed sequentially and connecting a dispatcher's office and a plurality of way stations, of a source of current in said dispatcher's office common to all of said message circuits, of means for including in a particular message circuit a source of current of a particular polarity at a distant way station, and means for reversing the polarity of said source at the dispatcher's office for said particular message circuit when the polarities of the two sources in said particular message circuit are cumulative, whereby said sources will there-

after oppose each other and result in the flow of very little current.

7. In a train dispatching system of the synchronous selector type, the combination with a plurality of message circuits closed sequentially and connecting a dispatcher's office and a plurality of way stations, means at a distant way station for including in a particular message circuit a source of current of a particular polarity under certain traffic conditions, and means at said dispatcher's office for neutralizing the effect of said source.

10 8. In a train dispatching system of the selector type, the combination with a plurality of message circuits closed one at a time and connecting a dispatcher's office and a plurality of way stations, of a source of current in said dispatcher's office common to all of said message circuits, and another source of current in each of said message circuits at the way station end of such message circuit, whereby message current will flow if the voltages of the sources of current in a particular message circuit are cumulative.

15 9. In a train dispatching system of the selector type, the combination with a plurality of message circuits closed one at a time and connecting a dispatcher's office and a plurality of way stations, of a source of current in said dispatcher's office common to all of said message circuits, another source of current in each of said message circuits at the way station end of such message circuit, and traffic controlled means for closing said message circuit at a point distant to said dispatcher's office.

20 10. In a train dispatching system of the selector type, the combination with a plurality of message circuits closed one at a time and connecting a dispatcher's office and a plurality of way stations, of a source of current in said dispatcher's office common to all of said message circuits, another source of current in each of said message circuits at the way station end of such message circuit, and traffic controlled means at such way station for at times closing said message circuit.

25 11. In a train dispatching system of the selector type, the combination with a plurality of message circuits closed one at a time and connecting a dispatcher's office and a plurality of way stations, of a source of current in said dispatcher's office common to all of said message circuits, another source of current in each of said message circuits at the way station end of such message circuit, and traffic controlled means for at times including said another source of current in such message circuit so as to be poled in one direction and at other times so as to be poled in the other direction.

30 12. In a train dispatching system of the selector type, the combination with a plurality of message circuits closed one at a time and

- connecting a dispatcher's office and a plurality of way stations, of a source of current in said dispatcher's office common to all of said message circuits, another source of current
 5 in each of said message circuits at the way station end of such message circuit, traffic controlled means at such way station for at times closing said message circuit, and means at the dispatcher's office for at times reversing
 10 the polarity of the source located at said dispatcher's office in a particular message circuit. 75
13. In a train dispatching system of the selector type, the combination with a plurality of message circuits closed one at a time and connecting a dispatcher's office and a plurality of way stations, of a source of current in said dispatcher's office common to all of said message circuits, of means for including in a particular message circuit a source of current of a particular polarity at a distant way station, and means for reversing the polarity of said source at the dispatcher's office for said particular message circuit when the
 25 polarities of the two sources in said particular message circuit are cumulative, whereby said sources will thereafter oppose each other and result in the flow of very little current. 80
14. In a train dispatching system of the selector type, the combination with a plurality of message circuits closed one at a time and connecting a dispatcher's office and a plurality of way stations, means at a distant way station for including in a particular message circuit a source of current of a particular polarity under certain traffic conditions, and means at said dispatcher's office for neutralizing the effect of said source. 85
15. In combination, a distant way station
 40 on a railway system, a central office, a circuit connecting said office and way station, polar indicating means and a source of current included in series in said circuit and at said office the polarity of said source being in a
 45 direction tending to operate said indicating means to the opposite position, means at said way station for including a source of current in said circuit of a polarity depending on traffic conditions at said way station, whereby said indicating means is operated only if the voltages of the two sources are cumulative. 95
16. In combination, a distant way station
 55 on a railway system, a central office, a circuit connecting said office and way station, polar indicating means and a source of current included in series in said circuit and at said office the polarity of said source being in a
 60 direction tending to operate said indicating means to the opposite position, means operated by said indicating means to reverse the polarity of said source upon each reversal of said indicating means, means at said way station for including a source of current in said 100
- 65 circuit of a polarity depending on traffic conditions at said way station, whereby said indicating means is operated only if the voltages of the two sources are cumulative. 105
- In testimony whereof I affix my signature. 70
